UNITED STATES PATENT OFFICE.

FLORENCE C. BIGGERT, JR., OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

SCALE GUARD.

Application filed January 6, 1925. Serial No. 927.

To all whom it may concern:

Be it known that I, FLORENCE C. BIGGERT, Jr., a citizen of the United States, residing at Pittsburgh, county of Allegheny, and

5 State of Pennsylvania, have invented a new and useful Improvement in Scale Guards, of which the following is a full, clear, and exact description.

The present invention relates broadly to 10 rolling mills, and more particularly to means cooperating therewith, and especially with the necks of the lower rolls for preventing the passage of slag or other foreign material to the roll bearings.

15 It has heretofore been customary in the art to which the present invention relates to provide the lower roll of a rolling mill with a supplemental groove adjacent each of the roll necks adapted to cooperate with 20 the down turned lip of a scale guard to prevent the passage of scale or other foreign material into the roll bearing.

In heavy mills, the roll spring makes it 25 desirable to make the rolls as short as possible while providing sufficient area for the work to be accomplished. It will be appreciated that the provision of supplemental grooves under such conditions are objectionable. Even with smaller mills, the construction 30 as heretofore used has represented a waste due to the increased length of the roll and the necessity of turning the guard groove therein.

35 In accordance with the present invention there is provided a scale guard effectively cooperating directly with the end of a roll and automatically held in contact therewith in such manner as to maintain at all times a seating relation between the guard and the 40 roll.

In the accompanying drawings there is shown for purposes of illustration only a preferred embodiment of the present invention, it being understood that the drawings 45 do not define the limits of my invention and that changes in the construction and the operation therein disclosed may be made without departing either from the spirit of the invention or the scope of my broader 50 claims.

In the drawings:

Figure 1 is an end elevation of a portion of a rolling mill showing my improved guard in position on the lower roll;

Figure 2 is a vertical sectional view 55 through a portion of the mill show in Figure 1;

Figure 3 is a side elevation, on an enlarged scale, of the improved scale guard;

Figure 4 is a longitudinal section through 60 the guard;

Figure 5 is an end elevation of the guard looking toward the left hand end as viewed in Figure 3, and

Figure 6 is an end elevation looking to- 65 ward the opposite end of the guard.

It has heretofore not been uncommon practice in the art of rolling mills to provide a substantially U-shaped bearing for the lower roll. This bearing being open 70 at its top must be shielded in order to prevent the access of objectionable foreign material thereto. By the present invention, advantage is taken of this general type of bearing and of the force of gravity for making pos- 75 sible the use of a scale guard which eliminates the necessity of extra long rolls and makes possible a sealing fit effectively preventing the passage of any objectionable material to the bearings. 80

In carrying out the present invention there may be provided a suitable roll housing 2 having provision for a U-shaped or open top bearing 3 for the lower roll. The upper edges of this bearing on each side of 85 the roll are shaped to provide ledges 4 fac- ing the roll neck 5. As illustrated in Figure 2 the upper edges of the bearing 3 are also shaped so that they are inclined down- 90 wardly toward the center of the roll stand. Due to this inclination, it will be apparent that an object placed on the bearing 3 will tend to gravitate toward the shoulder 6 at the end of the roll.

The improved scale guard operating in 95 accordance with this principle comprises a U-shaped body 7 having side edges providing projections 8 adapted to cooperate with the ledges 4, the parts interlocking to prevent lateral movement between the bearing and the guard whereby the parts are main- 100 tained in the desired assembled relationship. These edges are also of gradually decreasing height as clearly shown in Figure 3, the angle of inclination preferably corre- 105 sponding to that of the upper edges of the bearings 3. Due to this construction, the main body of the scale guard will be sup-

ported in substantially horizontal position, or in concentric relationship to the roll neck when mounted on the bearing, the entire guard being supported however on an inclined surface in such manner that it tends to move inwardly against the shoulder 6. This tendency is assisted by the jars incident to the operation of a mill.

The end of the guard adapted to contact with the shoulder 6 is formed with a thickened upwardly projecting flange 9 providing a substantial area of contact between the roll and the guard and also providing sufficient metal whereby the operation of the mill will grind an accurate seat between the guard and the roll.

While the accompanying drawings illustrate a preferred embodiment for taking advantage of the force of gravity and the jarring of the mill for providing the desired sealing it will be apparent that these advantages may be obtained by other embodiments involving the use of guards so mounted that they tend to move toward the center of the roll stand during the operation of the mill.

The advantages of the present invention arise from the provision of a guard effectively cooperating with the rolls without requiring any special sealing groove and without necessitating any increase in the overall length of the rolls.

The guard is readily replaceable so that new guards may be substituted as required, and at the same time permitting removal of the roll as may be necessary. Additional advantages of the present invention are obtained by reason of this construction.

I claim:

40 1. In a rolling mill a roll bearing, and a

scale guard cooperating therewith, said guard being constructed to move axially of the roll bearing during the operation of the mill, substantially as described.

2. In a rolling mill a roll bearing, a scale 45 guard cooperating therewith, and means causing said scale guard to tend to move axially of the roll bearing, substantially as described.

3. In a rolling mill a roll bearing, and a 50 scale guard cooperating therewith, said guard being constructed whereby it is normally urged in a predetermined direction substantially lengthwise of the roll by the force of gravity, substantially as described. 55

4. In a mill, a bearing, and a scale guard for said bearing having longitudinally inclined supporting means therefor, substantially as described.

5. As an article of manufacture, an improved scale guard for bearings comprising a body portion having longitudinally inclined supporting means therefor, substantially as described. 60

6. In a mill, a bearing having longitudinally inclined upper edges, and a scale guard cooperating with said inclined edges and longitudinally movable thereon, substantially as described. 65

7. In a mill, a bearing having longitudinally inclined upper edges, and a scale guard cooperating with said inclined edges and movable thereon, said guard also having longitudinally inclined supporting edges cooperating therewith, substantially as described. 70

In testimony whereof I have hereunto set my hand.

FLORENCE C. BIGGERT, JR.
